(57) **CLAIM**

The ornamental design for a protection knob, as shown and described.

DESCRIPTION

FIG. 1 is an upper front right perspective view of a protection knob showing our new design;

FIG. 2 is an upper rear left perspective view thereof;

FIG. 3 is a lower front right perspective view thereof;

FIG. 4 is a bottom view thereof;

FIG. 5 is a top view thereof;

FIG. 6 is a left view thereof;

FIG. 7 is a right view thereof;

FIG. 8 is a front view thereof; and,

FIG. 9 is a rear view thereof.

The broken lines shown in the drawings are included for the purpose of illustrating environmental structure and form no part of the claimed design.

1 Claim, 9 Drawing Sheets
